LOUD SPEAKER CABINET

Antonio Joseph Petruccelli, Mount Tabor, N.J., assignor
to Radio Frequency Laboratories, Inc., Boonton, N.J.,
a corporation of New Jersey

Filed June 27, 1960, Ser. No. 61,132

Term of patent 3½ years

(Cl. D26—14)

FIGURE 1 is a front elevational view of a loud speaker cabinet, showing my new design;

FIGURE 2 is a perspective view, taken from the right of FIGURE 1; and

FIGURE 3 is a perspective view, taken from the left of FIGURE 1.

The back of the loudspeaker cabinet is plain and unornamented.

I claim:

The ornamental design for a loud speaker cabinet, substantially as shown and described.
